CIRCUIT ARRANGEMENTS EMBODYING ELECTRON DISCHARGE DEVICES

Reginald Sidney Webley, Hayes, England, assignor to Electric & Musical Industries Limited, Hayes, Middlesex, England, a company of Great Britain

Application November 1, 1954, Serial No. 466,189

Claims priority, application Great Britain November 6, 1953

4 Claims. (Cl. 315—12)

This invention relates to circuit arrangements embodying electron discharge devices.

In the British patent specification No. 714,924, there are described various electronic storage tubes in which received signals can be applied to a charge storage target electrode by a so-called writing operation and the stored charges can be reproduced a number of times by a so-called reading operation. The reading operation is accomplished by scanning the target electrode with a low velocity electron beam in the presence of a longitudinal magnetic field and some of the electrons in the reading beam are modulated by the charges stored on the target electrode and pass through the latter to be collected by a collecting electrode to which is connected a signal impedance across which signals are developed. Some of the electrons in the reading beam are returned to the electron gun generating the reading beam where they are collected by the various electrodes comprising the electron gun such as a limiter electrode, a cathode shield, or the cathode.

An electron discharge tube suitable for television purposes is also known in which a photo-electrically sensitive target electrode is provided on to which an optical image is projected to be scanned by a low velocity scanning beam in the presence of a longitudinal magnetic field, the arrangement being such that the target electrode is stabilised at a potential corresponding substantially to that of the cathode of the electron gun which generates the scanning beam. In such a device electrons which are not required for discharging the target electrode are also returned to the electron gun generating the scanning beam. A further electron discharge device is also known in which the target electrode comprises a photo-conductive layer and such device is also arranged to be scanned in the presence of a longitudinal magnetic field by a low velocity scanning beam. In this device, electrons which are not collected by the target electrode are also returned to the cathode of the electron gun. In fact, in many electron discharge devices where an electron beam is arranged to scan a target electrode in the presence of a longitudinal magnetic field and with a low velocity such that the target electrode is caused to have an equilibrium potential corresponding substantially to that of the cathode of the electron gun generating the scanning beam, electrons which are not required to discharge the target electrode are returned to the electron gun.

Many proposals have been made in the past for employing the electrons which are not required to discharge the target electrode for the generation of required signals. In some cases an electrode such as a limiting electrode in the electron gun has been connected to earth through a signal resistance so that the current collected by this electrode and flowing through the resistance sets up the required signals. In this case, it is found that noise arises due to the fluctuation of the electron current from the cathode of the device which serves to decrease the signal-to-noise ratio.

2

It is the object of the present invention to provide an improved circuit arrangement by means of which electrons returned from the target electrode from a scanning beam can be employed to generate signals but in which the signal-to-noise ratio is improved.

According to the invention there is provided a circuit arrangement including an electron discharge device having a target electrode and an electron gun for generating a scanning beam which is caused to scan said target electrode and in which electrons not collected by the target electrode are returned to said electron gun and wherein the electrodes of said gun are interconnected for signal frequencies and have a high impedance-to-ground for said frequencies and a signal frequency output is derived from the electrodes of said gun.

In order that the said invention may be clearly understood and readily carried into effect, it will now be more fully described with reference to the single figure of the accompanying drawing, which illustrates a circuit arrangement in accordance with the invention and as applied to one of the electronic storage tubes disclosed in the specification of the aforesaid patent.

The storage tube shown in the drawing is particularly suitable for radar purposes, and comprises an evacuated envelope 1 having at one end a cathode 2 for generating a beam of electrons, a modulating electrode 3, an anode 4, and an electron collecting electrode 5. In the enlarged centre portion of the envelope 1 there is provided an electron permeable charge storage target electrode 6 which comprises a metal mesh or grid having, for example, a thousand meshes per linear inch and provided on its side facing the cathode 2 with a layer of insulating material such as calcium fluoride. Between the electrode 5 and the target electrode 6 there is provided a further mesh or grid 7 which may function as an electrostatic shield. At the other end of the tube there is provided a further cathode 8 adapted to generate a beam of electrons, a cathode shield 9, a beam limiting electrode 9a, an anode 10 which extends close to the target electrode 6, and between the cathode 8 and the electrode 6 there is provided a mesh or grid 11 which functions as an ion trap. The electron beam from the cathode 2 is scanned over the surface of the target electrode 6 in any suitable manner, as by means of scanning coils indicated at 12 and the electron beam from the cathode 8 is also scanned over the opposite surface of the storage electrode as by means of scanning coils 13, the beam from the cathode 8 being caused to scan the target electrode at a low velocity and in an orthogonal manner for which purpose the beam from the cathode 8 is caused to scan in the presence of a longitudinal magnetic field generated by a solenoid coil 14.

In operating the tube shown in the drawing, the cathode 2 may be maintained at a negative potential of 1500 volts and the modulating electrode 3 is connected to a source 15 of signals which may, for example, be signals derived from radar apparatus. The anode 4 may be maintained at a positive potential of 50-100 volts and the collecting electrode 5 may be connected to a positive potential of about 35 volts. The grid or mesh 7 may be maintained at the potential of the electrode 5 or at a more positive potential with respect thereto as hereinafter referred to. The cathode 8 may be maintained at zero volts, the cathode shield 9 at a negative potential of about 30 volts, the limiter 9a at a positive potential of about 600 volts and the anode 10 and the ion trap mesh 11 at a positive potential of about 400 volts. The conducting member of the target electrode is maintained at a potential of between -2 and +5 volts with respect to the cathode 8. The signs of the potentials applied to the various electrodes referred to above and hereinafter are taken in relation to the potential of the cathode 8. The electron beam

from the cathode 2 serves to perform the writing operation and the electron beam from the cathode 8 the reading operation. In order to cause the target electrode to store charges corresponding to signals from the signal source 15, the potential applied to the electrodes associated with the cathode 2 are such that the beam from the cathode is caused to impinge on the insulating layer of the target electrode with a velocity greater than that corresponding to the first cross-over point on the secondary electron emission curve of the insulating material so that a greater number of secondary electrons are released from the insulating surface compared with the incident electrons so that the insulating surface becomes charged positively. The order of positive charging of said insulating surface may be 2-3 volts with respect to the potential of the cathode 8. The potential applied to the conducting member of the target electrode is a few volts positive or negative with respect to the cathode 8 so that during a reading operation the number of electrons of the reading beam from the cathode 8 which actually pass through the target electrode will depend on the stored charge in the vicinity of the beam and hence the electrons will be modulated by the stored charges. The electrons passing through the target electrode from cathode 8 are collected by the electrode 5.

The electrons during a reading operation which do not pass through the interstices in said target electrode are returned to the electron gun comprising the cathode 3 and the electrodes 9 and 9a and the required signals are generated from these electrons. For this purpose the electrodes 8, 9 and 9a have a high impedance-to-ground for the signal frequencies and as shown the electrode 9a is connected through, for example, a 1 megohm resistance 16 to a positive source of potential of about 600 volts and the cathode 8 is also connected through a resistance 17 of about 1 megohm to a point of negative potential of 150 volts. The electrode 9 is also connected through a resistance 18 of about 4.7 megohms to a source of negative biasing voltage. Furthermore, the electrodes 8, 9 and 9a are inter-connected for producing output signal frequencies for which purpose these electrodes are intercoupled by means of condensers 19 and 20. Thus, the electrons which are returned from the target electrode 6 and which will be collected, in the main, by the limiting electrode 9a and also by the cathode 8 and possibly by the electrode 9 serve to set up signals or, in other words, the net current leaving the cathode 8 serves to generate signals which are fed through a condenser 21 to an amplifier 22 and then to a reproducing tube 23. It will be appreciated from the above arrangement that the signal-to-noise ratio is improved since the noise associated with the flow of current between the cathode and limiter electrode 9a flows in a closed circuit which does not contain any signal impedance.

It may be found that when the voltage on the electrode 9 is changed, an undesired change in the potential of the cathode 8 occurs and it is accordingly preferred to employ in the circuit a suitable voltage stabiliser for the cathode potential, such a voltage stabiliser comprising a known type of thermionic valve stabiliser employing, for example, a pentode valve 24 in which voltage stabilisation is effected by means of negative feedback from the anode to the control electrode thereof. As shown, the cathode 8 is connected to the control electrode of the valve 24 through a resistance 25 which may have a value of 4.7 megohms, the control electrode being connected through a condenser 26 to earth. The screen electrode of said valve is connected to a positive supply terminal of, say, 300 volts through a resistance 27 and the anode of the valve is connected through a load resistance 28 of, say, 100,000 ohms to said positive supply terminal. The anode of the valve 24 is also connected through a resistance 29 to the control electrode for providing a negative feedback, whereby the valve 24 functions in well-known manner to stabilise the cathode potential of the cathode 8 which in

the example referred to above is zero. The dotted line 30 indicates a screening enclosure for the parts contained within said enclosure and this screening enclosure is connected to earth. The various supply leads are decoupled to earth by the condensers 31 and resistances 32 and 25 as shown.

If desired, signals can also be generated across a signal resistance connected to the electrode 5 and employed in conjunction with the signals fed to the amplifier 22 via the condenser 21 for application to the reproducing tube 23, one of the generated signals being suitably reversed in phase and if necessary equalised in amplitude.

With the arrangement in accordance with the present invention in order to erase the charges on the electrode 6 the electrostatic shield 7 can be maintained at a negative potential with respect to the cathode 8 generating the reading beam without cutting-off the modulated beam which passes through the target electrode so that the electrons of said modulated beam return to said target electrode and discharge the latter, so that thereby it is possible to obtain minimum erasure times of less than 1 second. With the arrangement according to the invention, the writing gun anode 4, can be connected to the collector electrode 5 and both of these electrodes can be maintained at a positive potential with respect to the cathode of the reading gun. Furthermore, the electrode 7 may be maintained at a positive potential with respect to the collector electrode 5.

Although the invention has been particularly described as applied to the storage tube shown in Figure 1 of British patent specification No. 714,924, it will be appreciated that it can also be applied to the tube shown in Figure 3 of said patent specification and also to other electron discharge devices having a target electrode which is scanned by a low velocity scanning beam in the presence of a longitudinal magnetic field such as the devices referred to in the preamble of this specification. In all applications of the invention, the signals set up at the electron gun and the signals generated from the collector electrode can be employed in push-pull if so desired.

What I claim is:

1. A circuit arrangement including an electron discharge device having a target electrode, an electron gun spaced therefrom for generating a scanning beam, said gun including a cathode and a further electrode disposed near to said cathode and disposed to collect electrons, means to cause said beam to scan said target electrode with a low velocity, means to cause electrons not collected by the target electrode during scanning to be returned to said cathode and further electrode to generate output signals, said last named means including means surrounding the space between said gun and target electrode to generate a magnetic field, means interconnecting said cathode and said further electrode for deriving output signal frequencies, means connected to said last named means to provide a high impedance to ground for said frequencies and means connected to said high impedance providing means for deriving a signal frequency output from said cathode and further electrode.

2. A circuit arrangement including an electron discharge device having a target electrode, an electron gun spaced therefrom for generating a scanning beam, said gun including a cathode, a cathode shield and a further electrode disposed near to said cathode and disposed to collect electrons, means to cause said beam to scan said target electrode with a low velocity, means to cause electrons not collected by the target electrode during scanning to be returned to said cathode, cathode shield and further electrode to generate output signals, said last named means including means surrounding the space between said gun and target electrode to generate a magnetic field, condensers interconnecting said cathode and said further electrode for deriving output signal frequencies, a high impedance connecting said cathode, cathode shield and said further electrode to points of suitable po-

tential and means for deriving a signal frequency output from said cathode, cathode shield and said further electrode.

3. A circuit arrangement including an electron discharge device having an electron permeable charge storage target electrode, an electron gun spaced therefrom for generating a scanning beam, said gun including a cathode and a further electrode disposed near to said cathode and disposed to collect electrons, means to cause said beam to scan said target electrode with a low velocity, an electron collecting electrode to collect electrons which pass through said target electrode, a mesh between said target electrode and said collecting electrode, means to cause electrons not collected by the target electrode during scanning to be returned to said cathode and further electrode to generate output signals, said last named means including means surrounding the space between said gun and target electrode to generate a magnetic field, means interconnecting said cathode and said further electrode for deriving output signal frequencies, means connected to said last named means to provide a high impedance to ground for said frequencies and means connected to said high impedance providing means for deriving a signal frequency output from said cathode and further electrode.

4. A circuit arrangement including an electron discharge device having an electron permeable charge storage target electrode, an electron gun spaced there-

from for generating a scanning beam, said gun including a cathode, a cathode shield, and a further electrode disposed near to said cathode and disposed to collect electrons, means to cause said beam to scan said target electrode with a low velocity, an electron collecting electrode to collect electrons which pass through said target electrode, a mesh between said target electrode and said collecting electrode, means to cause electrons not collected by the target electrode during scanning to be returned to said cathode, cathode shield and further electrode to generate output signals, said last named means including means surrounding the space between said gun and target electrode to generate a magnetic field, condensers interconnecting said cathode and said further electrode for deriving output signal frequencies, a high impedance connecting said cathode, cathode shield and said further electrode to points of suitable potential and means for deriving a signal frequency output from said cathode, cathode shield and said further electrode.
